US00D612043S

(12) **United States Design Patent**
Young et al.

(10) **Patent No.:** US D612,043 S
(45) **Date of Patent:** ** *Mar. 16, 2010

(54) **ENDOTRACHEAL TUBE**

(75) Inventors: **Peter J. Young**, King's Lynn (GB);
Archie I. J. Brain, Mahe (SC)

(73) Assignee: **International Patents Inc.**, Mahe (SC)

(**) Term: **14 Years**

(21) Appl. No.: **29/306,974**

(22) Filed: **Apr. 21, 2008**

(30) **Foreign Application Priority Data**

Oct. 25, 2007 (EM) 000818539

(51) **LOC (9) Cl.** **24-02**

(52) **U.S. Cl.** **D24/112; D24/115**

(58) **Field of Classification Search** **D24/110, D24/111, 112, 115, 121; 604/96.01, 101.01, 604/104, 508, 509; 128/207.15, 207.16, 128/200.26; 623/9**

See application file for complete search history.

(57) **CLAIM**

The ornamental design for an endotracheal tube, as shown and described.

DESCRIPTION

FIG. 1 is a top, front and left side perspective view of an endotracheal tube in a first position in accordance with the present invention;

FIG. 2 is bottom, front and right side perspective view of an endotracheal tube in a second position in accordance with the present invention;

FIG. 3 is a front plan view of the endotracheal tube shown in FIG. 2;

FIG. 4 is a front plan view of the endotracheal tube shown in FIG. 1;

FIG. 5 is a bottom, rear and left side perspective view of the endotracheal tube shown in FIG. 2; and,

FIG. 6 is a rear plan view of the endotracheal tube shown in FIG. 1.
